UNITED STATES PATENT OFFICE.

THOMAS DOODY, OF DULUTH, MINNESOTA.

INTERCHANGEABLE HEEL FOR SHOES.

1,148,363.

Specification of Letters Patent. Patented July 27, 1915.

Application filed September 26, 1914. Serial No. 863,651.

To all whom it may concern:

Be it known that I, THOMAS DOODY, a citizen of the United States, residing at Duluth, in the county of St. Louis and State of Minnesota, have invented certain new and useful Improvements in Interchangeable Heels for Shoes, of which the following is a specification, reference being had therein to the accompanying drawing.

10 My invention relates to improvements in interchangeable heels for shoes.

The object of my invention is to provide a heel which can be readily attached or detached from the shoe so that it can be interchanged from the left to the right shoe to cause an even wearing of the heel and thus prevent the same from running over.

Another object of my invention is to provide a simple, cheap and effective heel of this character having certain details of structure hereinafter more fully set forth.

In the accompanying drawings: Figure 1 is a bottom plan view of a shoe showing the heel removed. Fig. 2 is a vertical sectional view of a shoe showing my heel applied thereto. Fig. 3 is a top plan view of the removable heel. Fig. 4 is a perspective view one of the spring sockets for locking the heel to the shoe.

30 The actual wear upon a heel of a shoe is invariably upon one side or the other and when it is possible to interchange the heels from time to time, it will be seen that the heel will wear evenly and the life thereof will necessarily be materially increased.

Referring now to the drawing, 1 represents a portion of a shoe-welt having an abnormally low heel 3, rigidly fixed thereto in the usual manner. Secured into the lower 40 face of the heel 3, are a plurality of screws 4, preferably three in number, which have their heads projecting some distance from the lower face of the heel 3 to admit of their being surrounded by spring sockets, which 45 will be hereinafter more fully described.

While I have shown three screws used for the purpose of securing the detachable heel to the portion 3 of the heel, yet it will be understood that any number could be used 50 having a large head.

The interchangeable portion 7 of the heel is preferably made of two layers 8 and 8', the upper layer 8 having openings to fit the sockets 5. These sockets 5, as shown,

are formed of spring metal of a cylindrical shape having the base 8² integral therewith and which is considerably larger in diameter than the socket and forming an annular flange 9 thereabout. This flange 9 is placed between the layers 8 55 and 8' of the detachable heel and acts as a securing means for the socket, while the socket 5 proper lies within the openings 9' in the upper layer 8 of the detachable heel and has its upper end flush therewith so that 60 the detachable heel will rest against the lower face of the low heel portion 3 carried by the welt 1.

The socket 5 is divided longitudinally into two sections by the slots 10 to admit of the 70 socket expanding so that it can be forced over the head of the screws 4 and is made of metal having sufficient resiliency for this purpose and is slightly bulged as at 11, so that the socket will take a firm hold upon 75 the screw-head when forced over the same.

While I have shown and described the invention as applied to a leather heel, it will be understood that the same would operate with equally good results if used with the 80 rubber heels and affords a simple, practical and cheap means for providing an interchangeable heel. This structure is also of such a nature that the heel is held upon the shoe against ordinary strain to which 85 it is subjected and yet can be readily removed when desired.

When the heels have become worn slightly on one edge, they are taken off and placed upon the opposite shoe. That is if it is 90 upon the left shoe, it is placed upon the right one and vice versa, and thus bring the unworn portion of the heel at a point where the wear takes place and thus cause an even wearing down of the heel. 95

Having thus described my invention, what I claim and desire to secure by Letters Patent is:

The combination with a shoe having a low heel, round-headed screws secured to the 100 lower face thereof, a removable and interchangeable heel consisting of two layers secured together, and sockets embedded within the upper layer of the interchangeable heel and 105 consisting of approximately cylindrical resilient body portions outwardly bulged, the said resilient body portions receiving and

clamping the heads of the screws, the lower end of the body portion having an annular flange resting between the layers of the interchangeable heel, the said round-headed screws adjustable in and out of the sockets providing means for compensating for the wear of the heel.

In testimony whereof I hereunto affix my signature in the presence of two witnesses.

THOMAS DOODY.
